UNITED STATES PATENT OFFICE.

HERMAN REUTER, OF WARSAW, ILLINOIS.

WIND-WHEEL REGULATOR.

SPECIFICATION forming part of Letters Patent No. 658,398, dated September 25, 1900.

Application filed May 17, 1900. Serial No. 17,016. (No model.)

To all whom it may concern:

Be it known that I, HERMAN REUTER, a citizen of the United States, residing at Warsaw, in the county of Hancock and State of Illinois, have invented certain new and useful Improvements in Wind-Wheels; and I do declare the following to be a full, clear, and exact description of the invention, such as will enable others skilled in the art to which it appertains to make and use the same, reference being had to the accompanying drawings, and to the letters of reference marked thereon, which form a part of this specification.

This invention relates to wind-wheels of the vertical type, and has for its object the production of a comparatively simple and inexpensively-constructed appliance of this character possessing advantages in point of efficiency and reliability in its automatic regulation and also of ready accessibility to the wind-wheel top.

The nature of the invention will be readily comprehended, reference being had to the following detail description and to the accompanying drawings, in which—

Figure 1 is a side elevation of a wind-wheel embodying my invention. Fig. 2 is an enlarged elevation, partly broken away, of the opposite side of the wind-wheel. Fig. 3 is an enlarged detail view of the automatic regulating mechanism, showing in full and dotted lines the positions of the vane when in and when out of the wind. Fig. 4 is a sectional view on line 4 4 of Fig. 3. Fig. 5 is a detail view of the base of the tower.

Referring to the said drawings by letter, A denotes the wind-wheel, which is mounted to rotate on a top frame B, pivotally supported on the tower. Hinged to the rear of the top frame to flex in but one direction is the vane C. The pump-rod is operatively connected with the wind-wheel to be reciprocated by any suitable mechanism including a pitman A'. At one side of the top frame is vertically mounted a drum D, and D' is a disk horizontally rotatable with the drum and provided with a stop-pin d, which acts, in connection with the upper drum and disk-supporting bracket e, to limit the range of movement of the disk and drum.

d' is a chain which is attached at one end

to the drum and at its other end to an arm extending out from the vane C. The rotation of the drum operates to move the vane out of the wind, this being automatically accomplished when a predetermined level of water in the tank has been reached. The mechanism for effecting the rotation of the drum consists of a pawl g, one end of which is pivotally attached to an arm g', carried by a lever g². This lever is fulcrumed at its outer end on the bracket e, its inner end being pivotally connected with the pitman A' to move therewith. The other or engaging end 60 of the pawl g is in the path of an annular series of shoulders d² d², provided in the upper side of the disk D', said shoulders being formed, preferably, by holes in the disk, as shown, and in the movement of the pitman 65 the pawl g, through the lever g² and arm g', engages a shoulder d² of the disk and partially rotates the latter and drum, with the result of flexing the vane. In the reciprocations of the pitman the pawl is caused to 70 engage the shoulder d² successively, such engagements taking place in the forward movements of the pawl, and in the rearward movements thereof it rides freely over the shoulders, but is depressed into their 75 path by the action of a coiled spring g³. The disk and drum, and consequently the vane, are held against return movement by a stop-pawl h, pivotally attached to uprights i, carried by the frame B, the free end of the stop-pawl being held against the shoulder by a 80 coiled spring h', attached to said pawl and to the uprights. Normally the pawls g and h are elevated out of engagement with the shoulder d² of the disk and the vane is in the 85 wind. Such elevation of the pawls is effected by a float j, which is connected with the pawls by a wire or cord j' and which is of sufficient weight to overcome the action of the springs g³ and i'. The wire or cord j' is directly connected at its upper end to a lever k, centrally fulcrumed on the uprights i, and k' k² are wires which connect the other end of the lever k with the pawls g and h, respectively. The float j is arranged in the tank, and until 90 the level of water in the tank has reached a predetermined point the weight of the float keeps the pawls in disengaged position. When the water reaches the float, the cord j' 95 100

is relieved of weight and the pawls are brought by spring action into engagement with the disk-shoulders, and through the reciprocation of the pitman the parts are actuated to move 5 the vane out of the wind, the stop-pin d limiting such movement. When the water drops below the level aforesaid, the float acts as a weight to release the vane in the manner above stated.

10 The wind-wheel A carries at its inner side a disk or annulus a , the periphery of which serves as a braking-surface, and l is a brake-shoe which is brought by the flexing movement of the vane against the periphery of the 15 disk or annulus to check the rotation of the wheel. In the drawings the shoe is shown in releasing position. The shoe is attached to a slidably-supported stem l' , normally elevated by a coil-spring l'' , and a wire l''' leads 20 from the stem to one arm of a bell-crank lever l^4 , the other arm of the lever being connected by a chain l^5 with the vane opposite its pivoted side. A coil-spring l^6 , connected 25 with the top frame and with one of the lever-arms, restores the lever to its normal position, and said spring is made sufficiently stout to pull the vane into the wind after the vane is released. The flexing movement of the vane is thus employed to apply the brake to 30 the wind-wheel, with the result of rendering said wheel immovable when it is out of the wind.

The top frame is supported by a tower, preferably of the construction shown. Said 35 tower comprises a single post M, pivoted at or near its center to a base-frame M', comprising inclined braces m and m' , and a cross-brace m^2 serves as a shoulder against which the lower end of the post is brought when 40 the wind-wheel top is elevated. The post is held in upright position by an arm m^3 , which is movable to engage or to release the lower end of the post. The post is provided with a counterbalancing-weight m^4 , whereby but 45 little power is necessary to swing the post to elevate and lower the wind-wheel top.

A wind-wheel constructed in accordance with my invention is simple in construction, inexpensive to build, and is not liable to dis- 50 order. Moreover, the construction employed possesses advantages in point of efficiency and reliability in operation.

I claim as my invention—

1. In a wind-wheel, a vane hinged to flex in one direction, a drum vertically mounted 55 and having chain connection with the vane, a disk carried by the drum and provided on its upper side with an annular series of shoulders, a stop-pawl pivoted to the frame and engaging the shoulders in one direction, a 60 lever pivoted to the frame and connected with the pump-rod-actuating mechanism, an arm on the lever, a pawl pivoted to the arm and adapted to engage the disk-shoulders successively to rotate the drum and flex the vane, 65 a float, and a connection between the float and pawls, the float operating normally to disengage the pawls from the shoulders.

2. In a wind-wheel, a vane hinged to flex in one direction, a drum having chain connection 70 with the vane, a disk carried by the drum and provided with an annular series of shoulders, a spring-depressed stop-pawl adapted to engage the shoulders, a reciprocating spring-depressed pawl adapted to engage 75 the shoulders to rotate the drum and flex the vane, a lever hinged to the frame and connected with the pump-rod-actuating mechanism, an arm on the lever to which the propelling-pawl is pivoted, a rock-lever pivoted 80 to the frame and connected at one end to the pawls, a float, and a connection between the other end of the rock-lever and float whereby movement of the latter is communicated 85 to the pawls.

3. In a wind-wheel, a vane hinged to flex in one direction, a drum having chain connection with the vane, means controlled by a float for automatically rotating the drum to flex the vane, a bell-crank lever pivoted 90 to the frame one arm of which has chain connection with the vane opposite its hinge, an annulus carried by the wheel, a brake-shoe carried by a spring-elevated stem, a cord connecting the stem and the other arm of the lever, and a spring connected to said latter arm and the frame and operating to restore the vane to its normal position.

In testimony whereof I affix my signature in presence of two witnesses.

HERMAN REUTER.
